UNITED STATES PATENT OFFICE

113,041

DESIGN FOR A DISPLAY STAND

Herman E. Lacy, Chicago, Ill.

Application November 14, 1938, Serial No. 81,072

Term of patent 14 years

To all whom it may concern:

Be it known that I, Herman E. Lacy, a citizen of the United States, residing at Chicago, in the county of Cook and State of Illinois, have invented a new, original, and ornamental Design for a Display Stand, of which the following is a specification, reference being had to the accompanying drawing, forming part thereof.

The figure is a perspective view of the display stand showing my new design.

I claim:

The ornamental design for a display stand, as shown.

HERMAN E. LACY.
